UNITED STATES PATENT OFFICE.

BUDD D. GRAY AND EDMUND W. RUBENCAME, JR., OF PHILADELPHIA, PENNSYLVANIA,
ASSIGNORS TO THE HESS-BRIGHT MANUFACTURING COMPANY, A CORPORATION OF
DELAWARE.

HEATING-FURNACE.

1,321,098.

Specification of Letters Patent.

Patented Nov. 11, 1919.

Application filed March 6, 1917. Serial No. 152,546.

To all whom it may concern:

Be it known that we, BUDD D. GRAY and EDMUND W. RUBENCAME, Jr., citizens of the United States, residing at Philadelphia, in the county of Philadelphia and State of Pennsylvania, have invented certain new and useful Improvements in Heating-Furnaces, of which the following is a specification, reference being had therein to the accompanying drawing.

This invention relates to heating furnaces and has reference more particularly to furnaces designed for heating comparatively small bars employed in the formation of the casing rings of antifriction bearings, the aim of the invention being to produce a furnace with a heating chamber in which the bars may be conveniently introduced and in which the heat will be uniformly distributed so as to subject the bars to a uniform and effective heating action with little or no liability of the formation of scale.

With this aim in view our invention consists of a furnace consisting of an inclosing body provided with a heating chamber and with a plurality of combustion chambers communicating therewith; the said chambers being of such improved form and combined in such improved relations that the heating gases will be uniformly and evenly distributed throughout the full extent of the heating chamber.

The invention consists also in providing the inclosing body with a heating chamber of elongated form and with a plurality of holes or openings extending through the wall thereof and communicating with the heating chamber through which holes the articles to be heated may be introduced into the chamber and supported therein so that they will be acted on uniformly by the heating gases.

The invention further consists of improved means for controlling the distribution of the heating gases in the heating chamber in order to maintain the same at a uniform degree throughout the extent of the chamber.

The invention consists also of certain improved details in the form and construction of the furnace which will be fully pointed out in the specification to follow and the novel features of which will be set forth in the appended claims.

In the accompanying drawings:

Figure 1 is a front elevation of a heating furnace having our invention embodied therein, certain parts being broken away and other parts shown in section.

Fig. 2 is a horizontal section through the same on the line *a—a* of Figs. 1 and 3.

Fig. 3 is a transverse sectional elevation on an enlarged scale on the line *b—b* of Figs. 1 and 3.

Referring to the drawings:

Our improved furnace comprises an inclosing body or casing 1 preferably of elongated form and of suitable material to withstand the high heat developed and to prevent the undue radiation of the same, the said body being formed with a front wall 2 and a rear wall 3. Within the inclosing body in rear of the front wall is an elongated heating chamber 4 which extends throughout the length of the body, and which at its upper end extends rearwardly in the form of a branch chamber 5 beneath an arch 6 connecting the upper ends of the two walls. 7, 8 and 9 designate combustion chambers which extend horizontally through the rear wall and communicate at their outer ends with openings 10 through which the combustible gases from the burners are introduced into the combustion chambers. These combustion chambers at their inner ends extend vertically as at 11 and communicate with the branch chamber 5, a vertical bridge wall 12 being arranged between the combustion chambers and heating chamber to deflect the incoming hot gases upwardly so that they will pursue a circuitous course before they enter the heating chamber. Fire bricks 13 are situated in the combustion chambers in rear of the bridge wall in such position that the incoming heating gases will impinge against them and be deflected upwardly, the bridge wall being thus protected from the direct effect of the gases.

Flues 11^a lead from the base of the heating chamber rearwardly and then upwardly between the combustion chambers, and at the outer side of the same and communicate with the outside atmosphere.

Extending through the front wall of the furnace are a plurality of circular holes or openings 14 arranged at intervals side by side with their inner ends communicating with the heating chamber so that the arti-

cles 15 to be heated, in the present instance in the form of round bars, may be introduced into the heating chamber and their ends exposed to the heating gases, a horizontal ledge 16 being provided in the heating chamber in such position that the inner extremities of the bars will rest thereon and be supported thereby. This ledge projects forwardly, as shown in Fig. 3, from the 10 front face of the bridge wall, which latter constitutes in effect a shoulder extending upwardly from the ledge and in position to have the inner ends of the bars to be heated abutted thereagainst, in order to determine 15 the extent of insertion of the bars in the heating chamber. The openings 14 are of a size to conform rather closely to the cross sectional form of the bars and are lined with fire brick or heat resisting collars 17, 20 whereby the entrance of air around the bars to the heating chamber will be prevented, and the formation of scale obviated.

Due to the construction described, and more particularly the arrangement of the 25 several combustion chambers side by side and communicating by circuituous paths with the elongated heating chamber at a plurality of points, the gases are distributed in a uniform manner throughout the extent 30 of the heating chamber and a uniform heat is maintained therein at all points in the length of the same, the flame of the burning gases being directed against the fire bricks as they enter the combustion chambers 35 whence the gases pass upwardly and over the bridge wall and are deflected downwardly by the arch into the heating chamber. The bars to be heated, with their inner portions projecting into the heating chamber 40 as shown in Fig. 3, will be acted on by the heating gases and be effectively and uniformly heated throughout the series.

We prefer in the operation of the furnace to prevent an absolutely complete combustion 45 of the gases and to maintain a reducing atmosphere at all times, there not being admitted sufficient air to furnish the required amount of oxygen necessary for complete combustion. In connection with this reducing 50 atmosphere, the comparatively close fit of the bars in the holes by preventing air from entering at that point, will effectively avoid the production and formation of scale.

It may sometimes happen that, due to the 55 non-uniformity of the combustible mixture furnished by the burners and due to other conditions, the heat may be more intense in one part of the heating chamber than in another part, and to meet this condition we 60 provide the flues 11^a with regulating dampers 18 to control the flow of the products of combustion to the outside. In the use of these flues for the regulation of the heat, if for instance it is found that the heat is 65 more intense toward the center of the cham-

ber, then the dampers of the two inner flues will be closed and the others opened, which will cause the products of combustion at the center to flow laterally toward the ends and thus develop more heat at the ends; and 70 if the heat is more intense at the ends of the chamber, the dampers of the end flues will be closed to cause the heating gases to flow toward the center.

The end walls of the furnace are provided 75 with openings 17 leading to the ends of the heating chamber, which openings are closed by removable caps or closures 19 so that access may be gained to the heating chamber when desired.

In the accompanying drawings and foregoing description we have set forth our invention in the particular detailed form which we prefer to adopt and which we have found in practice to answer to an admirable degree the ends in view. It will be manifest, however, to the skilled mechanic, that various changes may be made in the form and construction of the parts without departing from the limits of the 90 invention, and further it will be understood that the invention is not limited to any particular form or construction of the parts except in so far as such limitations are specified in the claims.

Having thus described our invention, what we claim is:

1. A heating furnace comprising an elongated inclosing body having therein a heating chamber extending lengthwise thereof 100 and closed at its top and ends, said body being provided with a plurality of openings extending through the front wall transversely of the length of the chamber for the introduction of the articles to be heated, 105 means for directing the heating gases from the rear in separate streams beneath the top of the chamber downwardly onto the articles projecting through said openings, and flues leading downwardly and rearwardly 110 from the heating chamber and communicating with the atmosphere.

2. A heating furnace comprising an inclosing body having a heating chamber therein closed at its top and ends, and having a plurality of openings extending through its front and communicating with the heating chamber for the introduction of the articles to be heated, said body being provided also with a plurality of independent combustion chambers adapted to receive the heating gases at their outer ends and communicating at their inner ends with the heating chamber.

3. A heating furnace comprising an inclosing body having a heating chamber therein closed at its top and ends, and having a plurality of openings through one wall thereof communicating with the heating chamber for the introduction of the articles 130

- to be heated, said body being provided also with a plurality of combustion chambers communicating at their inner ends with the heating chamber, and a bridge wall between 5 the combustion chambers and heating chamber to deflect the burning gases in their passage to the heating chamber.
4. A heating furnace comprising an in-closing body having an elongated heating chamber extending lengthwise thereof and having a plurality of openings through the front wall thereof transversely of the heating chamber and communicating with the same for the introduction of the articles to 10 be heated, said heating chamber having a rearwardly extending branch chamber at its upper end and said body being provided with a plurality of combustion chambers communicating at their inner ends with the 15 branch chamber.
5. A heating furnace comprising an in-closing body having an elongated heating chamber extending lengthwise thereof and having a plurality of openings through the front wall communicating with the heating chamber for the introduction of the articles to be heated, the said heating chamber having at its upper end a branch chamber extending laterally rearwardly, and said body being provided also with a plurality of combustion chambers at the rear communicating at their inner ends with said branch chamber, and a vertical bridge wall beneath the 20 branch chamber and between the combustion chambers and heating chamber.
6. A heating furnace comprising an in-closing body having therein a horizontal heating chamber, said body being provided with a horizontal opening extending through 25 the front wall thereof and communicating with the heating chamber for the introduction of the articles to be heated, a combustion chamber in the rear portion of the body communicating with the heating chamber, a bridge-wall between the combustion chamber and the heating chamber, and a horizontal edge extending forwardly from the bridge-wall in position to support the ends of the articles projecting through said openings; whereby the ends of the articles supported by said ledge may be lined up against the wall and uniform lengths of the articles 30 presented in the heating chamber.
7. A heating furnace comprising an in-closing body having therein a heating chamber, said body being provided with a plurality of openings extending through its front wall and communicating at their inner ends with the heating chamber for the introduction of the articles to be heated, said body being provided also with a plurality of combustion chambers adapted to receive the products of combustion at their outer ends and communicating at their inner ends with the heating chamber, fire bricks in the respective combustion chambers in the path of the incoming products of combustion, and a bridge wall in the rear of the fire bricks; whereby the burning gases will be deflected 35 upwardly as they enter the heating chamber.
8. A heating furnace comprising an in-closing body having a heating chamber therein at the front and having a plurality of independent combustion chambers at the rear communicating with the heating chamber, said body being provided with regulating flues communicating at their front ends with the base of the heating chamber and extending rearwardly therefrom and then upwardly between the combustion chambers 40 and discharging to the outside.
9. A heating furnace comprising an in-closing body having therein a heating chamber extending through the ends of the body, and having an opening through the wall thereof communicating with the heating chamber for the introduction of the articles to be heated, means for supplying heating gases to the chambers, and removable closures for the ends of said heating chamber to 45 permit access thereto.
10. A heating furnace comprising an in-closing body having therein a heating chamber, said body provided with a horizontal opening extending through the front thereof and communicating with the heating chamber for the introduction of the articles to be heated, a horizontal ledge in the heating chamber in position to support the inner portion of the article projecting through said opening, and a shoulder extending upwardly from the ledge in position to have the inner end of the article abutted 50 against it.

In testimony whereof, we have affixed our signatures.

BUDD D. GRAY.
EDMUND W. RUBENCAME, JR.
